UNITED STATES PATENT OFFICE.

ARTHUR MIDDLETON ROSE, OF YONKERS, NEW YORK, ASSIGNOR TO THE
W. & J. SLOANE, OF NEW YORK.

DESIGN FOR CARPET.

SPECIFICATION forming part of Design No. 27,233, dated June 15, 1897.

Application filed April 10, 1897. Serial No. 631,635. Term of patent 3½ years.

To all whom it may concern:

Be it known that I, ARTHUR MIDDLETON ROSE, a citizen of the United States, and a resident of Yonkers, in the county of Westchester, State of New York, have invented a new and original Design for Carpets and Borders, of which the following is a specification.

My design, as shown in the drawing, consists in a new design for the body and border 10 of a carpet.

In the drawing, A represents the body, and B the border.

The design A is characterized by an arrangement of scattered flowers, singly and in 15 small clusters, with foliage, and connected together by slender tendril-bearing stems or stalks, the whole somewhat loosely strewn upon the background. The main continuous tendril-bearing stem of flowers and foliage 20 along the center line of design A is faintly suggestive of the line of the festoon in the border design B.

The design B is characterized by an arrangement of festoons of flowers and foliage accompanied by leaf-like and conventional scroll-work with a central shell form and having between adjacent festoons depending spikes or pendants of flowers and foliage. 25

What I claim as new, and desire to secure by Letters Patent, is—

1. In a design for a carpet, the body A, substantially as shown.

2. In a design for a carpet, the border B, substantially as shown.

3. The design for a carpet, comprising the 35 body A and the border B, substantially as shown.

In testimony whereof I have signed my name to this specification in the presence of two subscribing witnesses.

ARTHUR MIDDLETON ROSE.
